UNITED STATES PATENT OFFICE.

VERNON B. STILL, OF PATCHOGUE, NEW YORK.

MUFFLER.

1,048,435.

Specification of Letters Patent. Patented Dec. 24, 1912.

Application filed April 4, 1912. Serial No. 688,432.

To all whom it may concern:

Be it known that I, VERNON B. STILL, a citizen of the United States, and a resident of Patchogue, in the county of Suffolk and State of New York, have invented a Muffler, of which the following is a full, clear, and exact description.

Among the principal objects which the present invention has in view is to provide for the elimination of sound accompanying the discharge of exhaust gases from internal combustion engines by absorbing the heat of the gases and thereby reducing the expansive force thereof to avoid back-pressure on the exhaust of an engine of the character named; and to provide a muffler the construction of which is simplified and economized.

One embodiment of the present invention is disclosed in the structure illustrated in the accompanying drawings forming a part of this specification, in which like characters of reference denote corresponding parts in all the views, and in which—

Figure 1 is a side view of a muffler constructed and arranged in accordance with the present invention shown in conjunction with a fragment of the hull of a vessel; Fig. 2 is a vertical longitudinal section of a muffler constructed in accordance with the present invention; Fig. 3 is a horizontal section taken on the line 3—3 in Fig. 2; Fig. 4 is a side view of a modified form of a muffler constructed and arranged in accordance with the present invention; Fig. 5 is a vertical longitudinal section of the modified form of the invention shown in Fig. 4; and Fig. 6 is a vertical longitudinal section of a modified form of the invention.

As seen in the accompanying drawings, the muffler consists primarily of a box-like casing 11, in the preferred form of which a dome 12 is raised above the upper wall of the said casing. Into the dome 12 is introduced both the hot expanding gases of an internal combustion engine and a jet of water preferably the water delivered from the cooling system of the engine. The exhaust gases are delivered to the dome 12 by the exhaust pipe 13, the said pipe delivering the gases at near the upper end of the dome. Intermediate the inlet of the pipe 13 and the outlet from the dome 12 to the chamber of the casing 11, the hot gases are passed through water which is introduced into the dome 12 by means of a pipe 14. The pipe

14 is provided with a spreader 15. The spreader 15 is arranged to deliver across the passage of the dome 12 a sheet of water attenuated and spread to a fan-shape, forming thereby a film through which the gas from the pipe 13 is compelled to travel to enter the chamber of the casing 11. The water thus introduced in the path of the heated gases being spread in the manner described is most readily converted into steam, the conversion absorbing the heat from the said gases and producing in the sheet of steam a violently acting expanding medium.

The unconverted water and the non-absorbed gas enters the chamber of the casing 11 and in the preferred form, as best seen in Figs. 2 and 3 of the drawings, they are delivered by the dome 12 directly to an outlet pipe 16. The delivery end of the pipe 16, as seen best in Fig. 1 of the drawings, is submerged in the medium floating the vessel in which the engine and muffler are installed to deliver the unconverted products or free water to the floating medium.

The lighter medium, steam or unabsoed gas, is conveyed by the pipe 17 and delivered to the atmosphere beyond the hull of the vessel above the line of submergence thereof. This lighter material is delivered to the pipe 17 after being passed through the baffle chamber. The gases and steam referred to enter the baffle chamber 18 by way of the passage 19, as seen best in Fig. 2 of the drawings. The passage 19 being at the top of the casing 11, and the inlet of the pipe 17 being at the bottom of the said casing, the gas and steam are compelled to pass between the plates 20 and 21. The plates 20 and 21 are joined to form a pile, and are relatively separated by means of connecting rods 22, 23. The plates 21 are each provided with a central opening or passage 23, and are each formed to a size to completely fill the space within the chamber 18. Between each of the plates 21 are disposed the plates 20. The plates 20 are formed to a diminished diameter arranged to provide an annular passage 24 about each of the said plates. By this arrangement it will be seen the unconverted gas and steam are compelled to follow a tortuous passage, alternately expanding to pass around the plates 20 and contracting to pass through the openings 23. In being thus acted upon by the plates 20 and 21 the rush or violent expanding of the gases

- ber provided with inlet and outlet ducts the inlet duct being connected with the exhaust of an internal combustion engine and the outlet duct being in communication with a body of liquid; an outlet for said chamber in open communication with the atmosphere; and a series of baffle plates to compel the escaping gases to follow a tortuous path alternately expanding and contracting.
- 10 4. A muffler having an expansion chamber; a contracted dome for said chamber; an inlet to said dome connected near the upper end thereof, said inlet being in open communication with the exhaust of an internal combustion engine; a water pipe to deliver into and crosswise said dome between the upper and delivery end of said

dome to form a water veil across said dome through which the exhaust products of said engine must pass; an exhaust duct for said expansion chamber; and a series of baffle plates interposed between said chamber and said exhaust duct to provide a tortuous path for the gases passing through from said chamber, said passage compelling alternate 25 expansion and contraction in the volume of said gases.

In testimony whereof I have signed my name to this specification in the presence of two subscribing witnesses.

AARON C. HORN, OF NEW YORK, N. Y.

COMPOSITION FOR WATERPROOFING CONCRETE.

1,048,695.

Specification of Letters Patent. Patented Dec. 31, 1912.

No Drawing.

Application filed February 28, 1912. Serial No. 680,525.

To all whom it may concern:

Be it known that I, AARON C. HORN, a citizen of the United States, and a resident of New York, in the county of New York and State of New York, have invented certain new and useful Improvements in Compositions for Waterproofing Concretes, of which the following is a specification.

This invention relates to a composition intended for waterproofing cement and concrete and relates in particular to a fluent or pasty composition, carrying a water-insoluble metallic soap, intimately incorporated with other waterproofing materials.

In waterproofing concrete and cement by what is known as the integral system, it is customary to incorporate small amounts of water soluble or water insoluble soaps. The water soluble soaps eventually combine with the lime of the cement to form a water insoluble lime soap. The water insoluble soaps either pre-formed or formed in the concrete mass are often not permanent in their waterproofing properties, for, in the course of time, under severe service conditions, some decomposition occurs which causes a reduction in the resistance of the mass to the ingress of moisture. This may be due partly to oxidation and partly to hydrolysis.

The present invention has for its object the production of a waterproofing composition, which is permanent in character and which, if desired, may be made in the form of a paste or fluent material, suitable for incorporating with the water used for gaging the cement.

While water insoluble soaps are prone to hydrolysis or other degenerative changes under severe service conditions, such compounds are not so susceptible to hydrolytic action when fortified by the presence of a drying oil, or other similar material.

The present invention comprises the use of a water insoluble soap, such as calcium stearate, or stearates, oleates, palmitates, linoleates, ricinolates, ceretates and the like, of such bases as barium, magnesium, calcium, zinc, manganese, iron, alumina, copper, etc. As a fortifying agent, I preferably make use of a drying oil, in particular Chinese wood oil, or tung oil, but I may also employ other drying oils, such as linseed, or perilla oil, or the semi-drying oils, such as

corn oil, cotton seed oil and peanut oil, 55 Boiled fish oil is also a useful fortifying agent. In addition to these oils which possess siccative properties to a greater or less degree, I also may use, to any desired extent, non-drying oils, such as petroleum oils of 60 various sorts, or coal tar oil, such as anthracene, or I even may make use of additions of tars, pitches, asphaltic bodies and the like.

In order to secure an intimate incorporation of the water insoluble metallic soap with the oily fortifying agent, I provide an emulsion forming compound, which may be either a water soluble soap, such as potassium stearate or sodium oleate, or other 70 similar soapy bodies, including the water soluble soaps of cotton seed, corn, fish, linseed and other saponifiable oils. Soaps may also be prepared from ordinary resin or similar resinous bodies by suitably saponifying. The emulsion forming agent may also be prepared from proteid material, such as glue or casein. The latter body is well adapted to form emulsions in aqueous alkaline solutions. Another emulsifying agent, 80 which is of a non-organic character is silicate of soda or the corresponding potassium compound.

When proteid bodies such as casein are used, it is important to have present a preservative agent. Inasmuch as the waterproofing material is distributed through a very great mass of concrete and is thus highly attenuated, ordinary preservatives do not afford satisfactory results and it 90 therefore becomes desirable to incorporate a preservative material which is capable of uniting with the casein compound so that a particle of preservative becomes attached to each particle of casein as it were, thereby 95 exerting a preservative action, irrespective of the degree of attenuation of the waterproofing compound. Casein may be brought into aqueous solution by means of an alkali such as ammonia, carbonate of 100 soda, borax and the like. It is desirable to use for this purpose a larger quantity of alkali than is desired in the final composition. Therefore I prefer to use an excess of alkali to dissolve the casein and to subsequently 105 neutralize a portion, at least, of the alkali by the addition of a quantity of acid after the casein has been dissolved. Also it is
